W. E. MASON

ARTIFICIAL LIMB

Filed Dec. 31, 1923

W. E. Mason, Inventor

Jack A. Shly.
Attorney

UNITED STATES PATENT OFFICE.

WESLEY E. MASON, OF DALLAS, TEXAS.

ARTIFICIAL LIMB.

Application filed December 31, 1923. Serial No. 683,588.

To all whom it may concern:

Be it known that I, WESLEY E. MASON, citizen of the United States, residing at Dallas, in the county of Dallas and State of Texas, have invented certain new and useful Improvements in Artificial Limbs, of which the following is a specification.

This invention relates to new and useful improvements in artificial limbs.

10 Considerable difficulty has been experienced by those wearing artificial legs attached to stumps, because of the substantially non-yielding sockets commonly used, which results in soreness and irritation, frequent requiring further amputation.

The object of the invention is to provide a socket having sufficient rigidity to hold its shape, but possessing ample resiliency and flexibility to make for comfort.

20 A particular object of the invention is to provide a flexible socket having a shell molded and shaped to fit the stump of the leg, but possessing rigidity as well as flexibility, thus making for comfort.

25 An important object is to construct the socket so as to take the weight off the end of the stump, thus relieving pain, irritation and soreness.

30 A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a rear elevation of a leg constructed in accordance with my invention,

40 Fig. 2 is an enlarged vertical sectional view on the line 2—2 of Fig. 1, and

Fig. 3 is an enlarged cross-sectional view on the line 3—3 of Fig. 1.

In the drawings the numeral 10 designates the foot of an artificial leg, 11 the ankle and 12 the shank of the leg. These parts may be of wood or any other proper material and may be suitably constructed. At its upper end the shank 12 is reduced to form a tenon 13 and a shoulder 14 at the base of the tenon.

50 The all important feature of the invention is a shell 15 receiving at its bottom, the tenon and resting upon the shoulder 14. This shell is formed in such a way as to possess suffi-

cient rigidity to hold its shape yet having ample flexibility to make a substantially "soft" socket for the stump of the wearer; and it must fit the stump without subjecting any particular part to an excessive strain. Shells are common in this art being built of various materials, but so far as I am aware after extensive investigations, all of those previous to my invention have been built up of stiff materials having little or no flexibility and depending upon the vent and its adjusting lace to get flexibility and this has not been satisfactory.

In making the shell I first take a plaster cast of the stump so as to obtain the exact contour and shape thereof. I then take a piece of sole leather or equivalent material and mold it to exactly fit the cast. I do not glue pieces together or build up layers in forming the shell, but use a single piece of leather. The making of the shell requires considerable skill and care. A shell thus formed will hold its shape, but will be flexible enough to yield readily to pressure.

The lower end of the shell is fastened around the tenon in any suitable manner. A facing or covering of thin leather or other finishing material 16 is glued to the outer surface of the shell and extends down onto the shank 12, so as to give a finished appearance. A lining 17 of felt or equivalent material, is fitted snugly within the shell and receives a finishing sleeve 18 of thin, soft leather, or equivalent material, which with the felt may be rolled over the top of the shell and suitably fastened.

The shell and parts 16, 17 and 18 are formed with a vent 19 in the rear of the socket. A tongue 20 extending up the inside of the socket protects the stump from the vent. An eyelet strip 21 is fastened on each side of the vent and receives a lace 22. This vent is used to tighten the socket around the stump and to give an adjustment when necessary, but it is not depended upon to give flexibility or resiliency to the socket.

Owing to the softness and flexibility of the socket the stump may be supported therein without touching at its lower end, thereby relieving the lower sensitive end of the stump from the irritation and soreness which results from contact, particularly with pads and the like. The flexible shell will

conform to the sides of the stump and will yield to the flexing of the muscles and cords, thus making for comfort and easy walking.

Various changes in the size and shape of the different parts, as well as modifications and alterations may be made within the scope of the appended claims.

What I claim, is:

1. In an artificial limb, a lower foot portion, an upper flexible socket formed of a single piece of leather molded to a precast form of the particular stump to be received

in the socket and having a laced vent at its rear side, a felt lining within the shell, and a finishing sleeve within said lining.

2. In an artificial limb, a lower foot portion, a flexible shell formed of one piece and fastened to the upper end of the foot portion, a facing covering the shell, a felt lining within the shell, and a finishing sleeve within the lining rolled with the lining over the upper edge of the shell.

In testimony whereof I affix my signature.

WESLEY E. MASON.
